[57] **CLAIM**

The ornamental design for a vehicle-wheel front face, as shown and described.

DESCRIPTION

FIG. 1 is a perspective view of a vehicle-wheel front face according to my new design;

FIG. 2 is a front elevational view thereof; and,

FIG. 3 is a side elevational view thereof.

Portions of the wheel depicted in broken line are for illustrative purposes only, and form no part of the claimed design.
